HANDRAILING

Wenzel W. Thom, Wichita, Kans., assignor of one-half to
Fannie Mae Jones, Wichita, Kans.

Filed Apr. 15, 1968, Ser. No. 11,466

Term of patent 14 years

Int. Cl. D25—02, 01

U.S. Cl. D13—7

Fig. 1.

Fig. 2.

Fig. 3.

Fig. 4.

Fig. 5.

FIG. 1 is a front elevational view of a handrail assembly, showing my new design;

FIGS. 2, 3 and 5 are cross-sectional views thereof taken on the lines 2—2, 3—3 and 5—5 respectively of FIG. 1; and

FIG. 4 is a fragmentary, enlarged, front elevational view of the lower part of the handrail assembly as shown in FIG. 3.

I claim:

The ornamental design for a handrail, as shown.
